UNITED STATES PATENT OFFICE.

CHARLES A. TATUM, OF NEW YORK, N. Y., ASSIGNOR TO WHITALL
TATUM COMPANY, OF SAME PLACE.

DESIGN FOR A BOX.

SPECIFICATION forming part of Design No. 34,569, dated May 28, 1901.

Application filed April 1, 1901. Serial No. 53,961. Term of patent 14 years.

To all whom it may concern:

Be it known that I, CHARLES A. TATUM, a citizen of the United States, residing at the borough of Manhattan, in the city, county, and State of New York, have invented and produced a new and original Design for a Box, of which the following is a specification.

The leading feature of my design is a box of substantially the configuration and representation shown in the accompanying drawings.

In the drawings, Figure 1 is a top view of the box. Fig. 2 is an underneath plan view, and Fig. 3 is a section on line 3 3 of Fig. 1.

The box illustrated is designed to contain an ointment or other unguent.

In the drawings, 1 represents the base of the box, which is of a general rectangular form and cross-section, as clearly appears from Figs. 2 and 3, having a central general rectangular portion receding from the base of the box, and 2 represents the body, having the curvilinear recess 3.

The box is represented as surmounted by a circular cover, as in Fig. 3. 25

What I claim is—

The design for a box substantially as herein shown and described.

CHARLES A. TATUM.
